UNITED STATES PATENT OFFICE.

ROBERT M. GILSON, OF PITTSBURGH, AND FRANK H. NICHOLSON, OF WILKINSBURG, PENNSYLVANIA, ASSIGNORS TO THE UNION SWITCH & SIGNAL COMPANY, OF SWISS-VALE, PENNSYLVANIA, A CORPORATION OF PENNSYLVANIA.

RAILWAY-SIGNAL.

1,258,404.

Specification of Letters Patent.

Patented Mar. 5, 1918.

Application filed May 12, 1913. Serial No. 767,112.

To all whom it may concern:

Be it known that we, ROBERT M. GILSON and FRANK H. NICHOLSON, citizens of the United States, residing, respectively, at 5 Pittsburgh, in the county of Allegheny and State of Pennsylvania, and at Wilkinsburg, in the county of Allegheny and State of Pennsylvania, have invented certain new and useful Improvements in Railway-Signals, 10 of which the following is a specification.

Our invention relates to railway signals.

We will describe one form of railway signal embodying our invention, and will then point out the novel features thereof in 15 claims.

In the accompanying drawings, Figure 1 is a sectional view showing one form of railway signal mechanism embodying our invention, the semaphore being omitted for 20 lack of space. Fig. 2 is a view showing in front elevation the case for the mechanism shown in Fig. 1 and also showing the semaphore. Fig. 3 is a view showing in rear elevation, with cover removed, the circuit controller shown in Fig. 1. Fig. 4 is a dia- 25 grammatic view showing one form of railway signaling system having applied thereto the signal shown in the preceding views. Fig. 5 is a sectional view on the line V—V 30 of Fig. 1, looking in the direction of the arrows.

Similar reference characters refer to similar parts in each of the views.

Referring first to Fig. 1, 27 is an outside 35 signal case (only the front portion of which is shown in Fig. 1) within which is mounted a gear-inclosing casing 13. The casing 13 is, as here shown, fixed to the front of case 27 by means of screws 13^a. Mounted in 40 suitable bearings in the casing 13 is a shaft 10 which projects through a suitable hole 4 in the case 27, and to the projecting end of which a semaphore 100 is fixed (see Fig. 2). This semaphore is biased by gravity to the 45 horizontal or danger position of indication, and is moved to one or more other positions by an electric motor as hereinafter explained. In the particular arrangement here shown, the semaphore 100 is moved 50 upwardly to a caution and a clear position, as indicated in dash lines in Fig. 2, but it is understood that the mechanism may equally well be arranged for the semaphore to be

moved downwardly from the horizontal position to its other positions of indication. 55

Fixed to the casing 13 is a cylindrical box 37 within which is journaled a spindle 15. The spindle 15 is connected with the semaphor 100 by means of suitable gearing which, as here shown, comprises a segmental gear wheel 26 fixed on the shaft 10, a pinion 24 and a gear wheel 23 rigidly connected and fixed on a shaft 25 journaled in the casing 13, a pinion 22 and a gear wheel 21 rigidly connected and mounted on ball bearings carried on the shaft 10, and a pinion 17 mounted on the spindle 15. 60

Mounted in the box 37 is an electric motor M, which is employed to move the semaphor 100 from its danger position to its 70 caution and clear positions. This motor is, as here shown, a two-phase induction motor comprising a stator 36, a stator winding 54, 55, and a rotor 11. The rotor 11 is carried by a spider 14 which is freely mounted 75 on the spindle 15 but is operatively connected therewith by means of a ratchet device R. This ratchet device is so arranged that when the motor is to move the semaphor 100, the rotor 11 is operatively connected with the spindle 15, but that the rotor 11 may rotate backward without an accompanying rotation of the spindle 15. It will be seen that by means of this ratchet device, the rotor 11 is rotated backwardly 80 while the semaphor 100 is returning toward its danger position, but that when the semaphor is stopped during this movement the rotor 11 is left free to rotate idly until its momentum is absorbed, thereby avoiding injury to the rotor due to sudden stoppage. Also, it will be seen that by causing the rotor 11 to be rotated backwardly by movement of the semaphor 100 toward its biased position, the motor may be employed to check 90 the movement of the moving parts while the semaphor 100 is returning toward the danger position in response to its bias, as hereinafter explained.

Mounted also in the box 37 is a holding 100 device H the purpose of which is to hold the semaphor 100 in the caution and clear positions. As here shown, this device H is an inductive device comprising a stator 29 fixed in the box 37, a stator winding 31, and 105 a rotor 48. The rotor 48 is carried by a

spider 12 which latter is fixed to the spindle 15 by a pin 32. The winding 31 is energized from a source of alternating current when the holding device H is to hold the signal, 5 as hereinafter explained.

Operatively connected with the shaft 25 is a shaft 25^a, which operates a circuit controller 28 for the control of the motor M and the holding device H as hereinafter 10 explained. This circuit controller 28 comprises a plurality of segments fixed on the shaft 25^a and co-operating with suitable stationary contact fingers; only two of these segments 64 and 69 are shown in Fig. 1, 15 but other segments and the contact fingers are indicated diagrammatically in Fig. 4.

The shaft 25^a operates another circuit controller 33, which latter I will now describe, referring to Figs. 1 and 3. This 20 circuit controller 33 comprises a back plate 35 provided with an annular projection 35^a which fits tightly inside of an annular socket in the end plate 40 of circuit controller 28. The back plate 35 is secured to 25 the end plate 40 by machine screws passing through holes 39 in the plate 35 and into tapped holes in plate 40. Shaft 25^a extends through a hole 38 in back plate 35. Mounted on the shaft 25^a is a rocker arm 30 43; this arm 43 is not fixed to the shaft 25^a, but is frictionally connected therewith so that as the shaft 25^a rotates, it tends to swing arm 43 in one direction or the other according to the direction of rotation of the 35 shaft. The friction between shaft 25^a and arm 43 is effected as follows: Referring to Figs. 1 and 5, 44 is a pin passing through the shaft 25^a and rigidly fixed therein. A circular block 45 of insulating material is 40 provided with a central hole adapted to pass over the shaft 25^a, and also with a diametrical slot 110 adapted to receive the pin 44. This block 45 is placed on the shaft and is held tightly against the pin 44 by means of 45 a nut 46 screwed onto the reduced and threaded end of shaft 25^a. It will be seen, therefore, that the block 45 is constrained to rotate with the shaft. Fixed to the shaft 25^a by means of a pin 42 is a cam 41, the 50 purpose of which will be explained hereinafter. Mounted on the shaft 25^a between the block 45 and the arm 43 is a coiled spring 47; this spring is under compression, so that it presses arm 43 against cam 55 41, thereby providing the desired friction between the arm 43 and the shaft 25^a. The arm 43 is provided with a downwardly projecting tongue 43^a. Mounted on one side of this tongue are a pair of insulating studs 60 51 which carry a contact finger 58, and mounted on the other side of the tongue are a similar pair of insulating studs 52 which carry a contact finger 59. Riveted to fingers 58 and 59, respectively, are contact springs 65 58^a and 59^a; each of which is bent back on

itself, and which carry at their outer ends contact blocks 60 and 61, respectively. These blocks 60 and 61 are adapted to make electrical contact with opposite sides of a stationary contact block 62 carried by a 70 terminal post 63 which is mounted in the back plate 35. It will be seen that when arm 43 is swung in counter-clockwise direction as viewed in Fig. 3, contact 62-61 is closed and contact 62-60 is open, and that 75 when the arm 43 is swung in the clockwise direction as viewed in Fig. 3, the former contact is open and the latter is closed. The angular movement of the arm 43 is limited by two screws 65 and 66 carried by the arm 80 43 and adapted to engage with a square stud 67 riveted in the back plate 35. This stud passes through a hole 68 in the arm 43, and the inner ends of screws 65 and 66 project into this hole.

85

The upper end of arm 43 is provided with a shoulder 72 which is adapted to be engaged at times by a dog 73 to prevent the arm 43 swinging into such position as to close contact 60-62. The dog 73 is carried freely by a stud 75 fixed in the back plate 35, and is biased to position for engagement with shoulder 72 by gravity and by a coiled spring 74 one end of which is fixed in the stud 75 and the other end in the dog 73. 95 This spring is under torsional stress. The dog 73 is, at the proper time in the operation of the signal, raised out of position for engagement with the shoulder 72 by the cam 41, which is the position of the parts 100 as shown in Figs. 2 and 3. The operation and purpose of the dog 73 and cam 41 will be explained hereinafter.

Projecting from the back plate 35 are two lugs 49 and 50. Fixed to the lug 49 are two 105 insulating studs 56 which carry an upwardly extending contact finger 77, and similarly fixed to lug 50 are two insulating studs 57 which carry an upwardly extending contact finger 76. These contact fingers 110 are adapted to make electrical contact with a segment 78 of electro-conductive material mounted on the block 45. The segment 78 is fixed to the block 45 by a bolt 79 passing through a hole in the block and through a 115 slot 80 in the segment. The slot 80 is arc-shaped and permits of angular adjustment of the segment 78 on the block 45.

The parts of circuit controller 33 are protected by a cover 71 which is held in place 120 by a nut 70 screwing on the reduced and threaded end of stud 67.

Referring now to Fig. 4, we have here shown four successive block sections, A, B, C and D of a railway track over which traffic moves normally in the direction indicated by the arrow. Traffic through block sections A, B and C, is governed by signals S, S', and S², located respectively adjacent the entering ends of these block sections. 130

These signals are controlled respectively by relays R , R' and R^2 , each of which relays, as here shown, comprises two windings 104 and 105, and two contacts 82 and 82^a ; 5 winding 105 is connected with the track rails of the block section over which the corresponding signal governs traffic and winding 104 is energized from a secondary 107 of a transformer T , T' or T^2 , the primary windings of which transformers are energized from signal mains 103. These signal mains are supplied with alternating signaling current from a suitable source, which source is not shown in the drawing. 10 Another secondary 108, of each of these 15 transformers is connected with the rails of the block section next in the rear through a pole changer 109 operatively connected with the adjacent signal. Each pole changer 109 may be included in the circuit controller 28 shown in Fig. 1, but is here shown as being of a different type for the sake of clearness. When winding 105 of each relay R , R' and R^2 is deenergized, 20 the armature occupies its middle position so that contacts 82 and 82^a are both open; when winding 105 of each relay is energized by current of one polarity relative to the current in the winding 104 of that relay, 25 the armature swings into such position that contact 82 is closed and contact 82^a is open; when winding 105 is energized with current of the opposite polarity relative to the current in winding 104 of the same relay, 30 the armature of that relay swings in the other direction to such position that contact 82^a is closed and contact 82 is open. The motor M and holding device H of each 35 signal are energized from secondary 107 of the adjacent transformer; the circuits for 40 these motors and holding devices are controlled by the relays R , R' and R^2 , and also by segments 64, 69 and 81 included in circuit controller 28 shown in Fig. 1; these 45 circuits are also controlled by circuit controller 33 shown in Fig. 1.

As shown in the drawing, block section B is occupied by a car or train W , so that signal S' indicates danger; block section C is 50 unoccupied, so that signal S^2 indicates "caution." It is understood that block section A and the next block section in advance are also unoccupied, hence signal S indicates clear.

55 When car or train W enters block section A, it deenergizes relay R , thereby opening the circuit of the holding device H for signal S , so that this signal changes to danger indication. When the entire car or train 60 passes out of block section B relay R' is energized in such direction that contact 82 is closed; the motor M of signal S' is then energized by the following circuit: from transformer 107, through wire 83, contact 65 82, wire 84, contact finger 85, segment 69,

finger 86, wire 87, then through motor windings 55 and 54 in parallel, resistance 34 being in series with winding 54, then through wire 88 to secondary 107. Current in this circuit will operate the motor M to move the signal S toward the caution position. During the movement of the signal from danger to caution positions, the friction between shaft 25^a and arm 43 swings this arm 43 to such position that contact 61-62 is closed. Just as the signal reaches the caution position the motor circuit just traced is opened by segment 69 leaving contact finger 86 so that the motor then stops. At this point the winding 31 of holding device H is energized through the following circuit: from secondary 107 through wire 83, contact 82, wires 84 and 89, contact 61-62, wire 90, finger 91, segment 64, finger 92, winding 31, wires 93 and 88 to secondary 107. The signal S^2 is, therefore, held in the caution position and the parts of the mechanism for this signal are then in the positions in which the parts of the mechanism of signal S' are shown in the drawing.

While signal S' was moving from danger to the caution position, pole changer 109 operated by this signal was reversed, thereby reversing relay R^2 so that contact 82^a of this relay is then closed. Motor M of signal S^2 is then energized through the following circuit: from secondary 107 of transformer T , through wire 83, contact 82^a , wire 94, finger 95, segment 81, finger 96, wires 97 and 87, through windings 55 and 54 of motor M , resistance 34 being in series with winding 54, then through wire 88 to secondary 107. Current in this circuit operates the motor M to move the signal to the clear position at which point the circuit just traced is opened by segment 81 leaving contact finger 96. Just as the clear position is reached, the holding device H is energized through the following circuit: from secondary 107 of transformer T^2 , through wire 83, contact 82^a , wires 94 and 98, finger 99, segment 64, finger 2, winding 31, wires 93 and 88 to secondary 107. The parts of the mechanism of signal S^2 then occupy the positions in which the parts of the mechanism of signal S' are shown in the drawing. Shortly before signal S^2 reaches the clear position, cam 41 engages dog 73 (see Fig. 3), raising the latter out of position for engagement with shoulder 72 so that arm 43 is then free to oscillate to its reverse position to close contact 62-60.

If, while signal S is in the clear position as shown in the drawing, a car or train should back into the block section next in advance of block section A, or should enter that block section from a siding, relay R would be reversed so that its contact 82 would be closed and its contact 82^a open. This would open the circuit of winding 31

of the holding device H for this signal so that the signal would then be free to return by gravity toward the caution position. As soon as this return movement begins, the 5 friction between shaft 25^a and arm 43 moves this arm to such position that contact 62—60 is closed. Then after the signal has moved to such point that segment 78 bridges contact fingers 76 and 77, motor M of this signal 10 would be energized through the following circuit: from secondary 107 of transformer T, through wire 83, contact 82, wires 84 and 89, contact 62—60, finger 77, segment 78, finger 76, wires 6, 97, and 87 then 15 through windings 55 and 54 of motor M, resistance 34 being in series with winding 54, then through wire 88 to secondary 107. It will be seen that the motor M is then 20 energized to produce torque in the same direction as when it is employed to move the signal, hence, the torque exerted by this motor will retard the movement of the signal so that the signal will be brought to rest. The point at which this motor circuit is closed by 25 segment 78 is preferably so chosen that the signal comes to rest about one degree below the caution position. Immediately after coming to rest the signal is moved a short distance toward its clear position by the 30 motor M, but after being thus moved one or two degrees, the friction between shaft 25^a and arm 43 moves this arm so that contact 62—60 opens, thereby deenergizing motor M and closing contact 61—62. The signal 35 S is then held in the caution position by the same circuit for winding 31 as traced hereinbefore in explaining how the signal is held in the caution position.

It will be seen from the foregoing that 40 while a signal is moving from the danger position to the caution or clear position, the arm 43 is locked by dog 73 in such position that contact 62—61 is closed and that the arm is unlocked only a short distance before 45 it reaches the clear position. Hence, it will be seen that the motor M can operate to retard the movement of the signal only while the latter is moving from the clear position toward the caution position.

50 Although we have herein shown and described only one form of railway signal embodying our invention, it is understood that various changes and modifications may be made therein within the scope of the appended claims without departing from the spirit and scope of our invention.

Having thus described our invention, what we claim is:

60 1. In combination, a signal biased to one position of indication, a motor connected with the signal to move the signal to another position of indication and to move with the signal while the latter is returning toward its biased position; a shaft 65 constantly connected with the signal, an arm

mounted on the shaft and adapted to oscillate, means for causing frictional engagement of said arm with said shaft, a circuit for the motor for causing the latter to retard the signal while returning toward its 70 biased position, a circuit controller for the control of said circuit and operated by said arm to be open when the arm is oscillated in one direction by movement of the signal away from its biased position and closed 75 when the arm is oscillated in the other direction by movement of the signal toward its biased position, a dog for holding said arm in such position that the circuit controller operated thereby is open and a cam operated 80 by said shaft for releasing said dog when the signal reaches a predetermined point in its movement.

2. In combination, a signal biased to danger position of indication, a motor operatively connected with the signal to move it to caution and clear positions, and to move with the signal while the latter is returning toward its biased position, means for holding the signal in the caution and clear positions, a circuit for said motor to retard the signal while returning toward the danger position in response to its bias, a circuit controller for the control of said circuit, and frictional means interposed between the 90 signal and the circuit controller tending to open the circuit controller while the signal is moving away from its biased position and to close the circuit controller while the signal is moving toward its biased position, means for locking said circuit controller open while the signal is moving away from its biased position, whereby if the signal returns toward its biased position before reaching a predetermined point the said circuit will not be closed, and means for releasing said locking means when the signal reaches said predetermined point in its movement.

3. In combination, a signal biased to danger position of indication, an electric motor operatively connected with the signal to move it to caution and clear positions and to move with the signal while the latter is returning toward its danger position, a 115 source of operating current for the motor, a circuit including said source for energizing the motor, a circuit controller for controlling said circuit, frictional means interposed between the signal and said circuit controller tending to open said circuit controller while the signal is moving away from its biased position and to close the circuit controller while the signal is moving toward its biased position, means for locking said circuit controller open while the signal is moving away from its biased position, means for releasing said locking 125 means when the signal reaches a predetermined point between the caution and 130

clear positions, and a second circuit controller operated by the signal for the control of said circuit, said second circuit controller being closed only during a portion 5 of the movement of the signal between the clear and the caution positions.

4. In combination, a signal biased toward one position of indication and capable of being moved away from said position against 10 the action of the biasing force, means for retarding the signal during its movement in response to its bias, and means frictionally connected with said signal and tending to throw said retarding means into or out 15 of operation according as the signal is moving in response to or in opposition to its biasing force, and other means controlled by said signal and operating while the signal is moving in opposition to its bias to 20 prevent said retarding means being thrown into operation by reversal of the signal until the signal has reached a predetermined point in its movement.

5. In combination, a signal biased to stop 25 position, a motor operatively connected therewith to move the signal to caution and clear positions in opposition to its bias and to move with the signal while the latter is returning in response to its bias, a member 30 frictionally operated by the signal and moved into one position or another according as the signal is moving in one direction or the other, two contacts controlled by said member one or the other being closed according 35 as said member occupies one position or the other, a circuit for the motor for causing the latter to arrest the signal near the caution position while returning toward its stop position, said circuit being controlled by the contact which is closed when 40 the signal is moving toward stop position, and a holding device controlled by the other contact for holding the signal in caution position.

45 6. In combination, a signal biased to one position of indication, a motor operatively connected therewith to move the signal to another position of indication and to move with the signal while the latter is returning 50 in response to its bias, two contacts controlled by said signal one or the other being closed according as the signal moves in one direction or the other, a circuit for the

motor controlled by the contact which is closed while the signal is moving in response 55 to its bias for arresting the signal, and a holding device controlled by the other contact for holding the signal.

7. In combination, a signal biased to one position of indication, a motor operatively 60 connected therewith to move the signal to another position of indication and to move with the signal while the latter is returning in response to its bias, two contacts controlled by said signal one or the other being 65 closed according as the signal moves in one direction or the other, a circuit for the motor controlled by the contact which is closed while the signal is moving in response to its bias for arresting the signal in an intermediate 70 position during such movement and for causing a slight movement of the signal in the opposite direction sufficient to reverse said contacts, and a holding device controlled by the other contact for retaining 75 said signal after said contacts have been reversed.

8. In combination, a signal biased to one position of indication, a motor operatively connected therewith to move the signal to 80 another position of indication and to move with the signal while the latter is returning in response to its bias, a circuit for the motor for causing the latter to retard the signal while returning in response to its bias, 85 a contact for controlling said circuit, means controlled by the signal tending to close or open said contact according as the signal is moving toward or away from its biased position, and means for locking said contact 90 in the open position while the signal is moving away from its biased position and for releasing said contact when the signal reaches a predetermined position during such movement. 95

In testimony whereof we affix our signatures, each in the presence of two witnesses.
